PAUL W. FRUTZMAN, OF LOS ANGELES, CALIFORNIA

APPARATUS FOR FIRE-FOAM PRODUCTION

Application filed September 28, 1927. Serial No. 222,569.

The art of extinguishing fires in general, and particularly oil fires, by means of "Foamite" or "Firefoam" is very well known and understood. It consists in bringing into admixture solutions of aluminum sulfate, hydrogen sodium carbonate (baking soda or more briefly soda), and a stabilizer or substance having the property of increasing the surface tension of aqueous liquids, such for instance as glue or licorice. It is customary to make one solution, known as the (a) or acid solution, of the aluminum sulfate alone, and another, known as the (b) or soda solution, of a mixture of soda and stabilizer and to make these two solutions of such strengths that their use in equal proportions will produce the largest yield of foam without wastage of chemicals.

By the admixture of said ingredients in solutions of the proper strength a very dense and tenacious foam is formed which, as it consists mainly of water and is sufficiently light to float on oil, is a highly efficacious and valuable agent for extinguishing fires.

It has heretofore been the custom either to prepare the solutions in advance and distribute them by means of duplicate pipe lines to such parts of a plant as require protection, or to store small quantities of the solutions in pressure tanks mounted on wheels, which can be taken to the seat of the fire. The first system is disadvantageous in that the required investment is very heavy, and more particularly in that the contents of the solution tanks is necessarily limited and the time required for recharging them quite extended. It has often occurred that these tanks have become exhausted in the course of a stubborn fire, and that before they could be refilled the fire had gotten quite out of hand.

The second system is disadvantageous in that the output in actual foam of the largest unit which can be taken from one point to another is so trifling that these portable tank units can handle only the smallest fires.

An object of my invention is to provide a cheap and effective means for the continuous production of solutions of the foam chemicals from their dry salts, thus doing away with the requirement for any storage of solu-

tion and avoiding a possible failure of solution during the course of a fire. In this view of my invention the apparatus is adapted to be used in connection with an existing system of duplicate distributing lines for solution.

A further object of my invention is to provide a simple and effective portable apparatus which can be taken to a point adjacent to the seat of the fire and there, being supplied solely with water and the two chemicals in bulk, will supply for an indefinite period streams of separate solutions of the two chemicals, which can be separately conducted to the actual fire and there intermixed in any preferred form of mixing head.

Further objects and advantages of my invention will be evident from an inspection of the accompanying drawing in which—

Fig. 1 is a view partly in elevation and partly in cross section, illustrating a complete embodiment of my invention in a preferred form. Fig. 2 is a diagrammatic view of an orifice plate showing parts thereof broken away.

Referring to the drawing, numerals 1 and 2 indicate conical bottomed steel tanks for preparing respectively the "a" and "b" solutions. 3 is an inlet pipe for water from any convenient source of supply, and 4—4 are gauge marks for indicating a constant height to which the tanks are to be kept filled.

Pipe 3 branches into two pipes 5^a and 5^b, controlled by the valves 6^a and 6^b, and the meters 31^a and 31^b shown in such lines are also convenient for determining the rate of flow of water, but are not essential. These pipes enter tanks 1 and 2 at substantially their bottoms, as indicated at 7—7, and beneath the umbrellas or inverted funnels 8—8. The upper ends of these funnels are made fast to the suction pipes 9^a—9^b but do not communicate therewith. The lower edges of the funnels are so formed as to closely approach the tank cones 10—10, leaving the annular openings 11—11 each of which should have approximately the area of an inlet pipe 5.

The pump suction pipes 9^a—9^b are made fast in the points of the cones and rise to a height of about six inches below the liquid

level marks 4—4. These pipes communicate with the suctions of the rotary or other suitable pumps 12^a and 12^b, driven at equal speed as by the pulley 13 from a common source of power not shown. If the unit is to be portable this source of power is preferably a dependable high-speed throttling gasoline engine, such for instance as the engine driving the truck on which the unit is mounted.

10 The pumps 12 discharge into lines 14^a—14^b by which the solutions pumped out of tanks 1 and 2 are conveyed through the lines 15^a—15^b (which may be of pipe, hose or both) to the mixing head 16 by which the solutions 15 are intermixed, converted into foam and directed onto the fire.

Between the lines 14^a and 15^a are interposed a control valve 17^a and a meter 18^a, the same fittings being correspondingly placed in 20 the "b" lines. A bypass line 19^a connects the discharge line 14^a with the water inlet 5^a, and in this bypass is placed the release valve 20^a so connected as to carry any excess discharge of pump 12^a back into tank 1. This bypass 25 enables the pump to be run at constant speed with any or no opening of the control valve 17^a. Similar connections are made in the lines connecting pump 12^b with tank 2.

Passing now to the top of the drawing 21^a 30 and 21^b are hoppers for receiving bulk supplies of dry powdered "a" and "b" chemicals, these hoppers being open at the top. 22 is a measuring device for feeding these chemicals in measured quantities, the device consisting 35 of three pistons 23—23—23 connected by a rod 24—24 and sliding in a cylinder 25—25. The assembly of pistons and rod is reciprocated by a single crank (or other suitable mechanism) 26 driven by a band wheel 27 at 40 some suitable speed which is proportioned to the speed of the engines driving the pumps.

In operation, these pistons, at the left end of their stroke, register the chambers 28^a—28^b with corresponding openings 29^a—29^b in the 45 bottoms of hoppers 30^a—30^b. At the right end of the stroke the openings 29 are closed and the powders contained in the chambers 28 are dumped into the corresponding chutes 30^a—30^b by which they are carried into tanks 50 1 and 2 respectively. It is considered advantageous to allow these powders to free themselves from air in the chutes 30 before passing into the bodies of liquid contained in the tanks, but they may if preferred be dumped 55 directly into the tanks and the chutes omitted. The relative quantities of powder carried by each chamber 28 may be varied by varying its length (without altering the piston stroke) or by wrapping a bulky material (such as rope or flax packing) around the rod.

It will be understood that this particular method of feeding the chemicals is not an essential part of my invention, and that other 65 means, such as screw conveyors or small buck-

et elevators may be used, provided they give a dependably constant feed of each powder.

In the operation of my device the following steps are taken. Water being connected to pipe 3, the valves 6^a and 6^b are opened until 70 the meters 31^a and 31^b indicate the predetermined rate of flow, that is, the rate at which solutions will later be pumped from the tanks. If the apparatus is to be used in a situation where the water pressure is reasonably constant, time in starting will be saved by providing stopcocks with dials and pointers, located as at 32^a—32^b, which can be left in adjustment, the valves 6^a—6^b being then used as stop valves only.

At the time the water flow is started the feed of dry chemicals is started, these passing instantly into solution as the fan of water issuing from the slot 11 picks up the powder which may reach the bottom of the 85 cone, this water fan setting up a high degree of turbulence which causes practically instant solution.

As soon as the solution level reaches the tops of pipes 9 the pumps 12 are started 90 with the discharge valves 17 closed, thus priming the pumps and discharging solution back into the bottoms of the tanks. The valves 17^a—17^b are then opened in unison until the meters 18^a—18^b show the desired 95 rate of flow of solution through the pipes 15^a—15^b to the mixing head 16. The final step is to readjust the water supply by means of the stopcocks 32 until the liquid stands 100 level in tanks 1 and 2 at the gauge marks 4—4.

These balancing up steps having been completed, the apparatus will continue to deliver, indefinitely, equal streams of solutions of correct strength, provided only that the hoppers be kept filled with their appropriate chemicals. At the termination of a run the tanks may be pumped empty by closing the water valves 6^a—6^b and opening the drain valves 33^a—33^b, the feed of chemicals having meanwhile been stopped.

While the apparatus illustrated in the drawing has the appearance of a large and permanent set, and while it may readily be constructed in such size, I would have it understood that it may also be constructed of such dimensions as to make it readily portable. For illustration, a unit producing 100 gallons per minute of each solution, equivalent, when properly mixed, to 2000 gallons per minute of foam (the rate of expansion being about ten to one), is sufficient to handle a very large fire. Such unit would require two pumps having a full speed capacity of say 125 gallons per minute, weighing about 150 pounds each. Tanks 1 and 2 should not have less than 1 minute capacity and preferably should hold a supply for 2 minutes, or 200 gallons each. The dimensions of such tanks would be about 3' diameter—130

ter, 3' 4" height on side and 2' height of cone.

The reagents weigh about 1 pound per 23 cubic inches, and as 100 gallons of "a" solution require 60 pounds and of "b" solution 40 pounds of reagent, a plunger 4" diameter making 20 strokes per minute would require an "a" chamber 6" long and a "b" chamber 4" long.

10 The water inlet main 3 should be say 3" diameter, branching to two 2" pipes, and the solution outlets should be 2" pipe size. The entire apparatus, including pumps, tanks, feed mechanism, valves and gauges, but not 15 including the motor (which would preferably be the truck motor) would weigh, empty, less than one ton, and could readily be mounted on a very small truck for transport to any point where water under pressure is available.

As replacing the control of the volumes of solutions and of water by means of valves and meters as shown, it is permissible, and is often a desirable modification of my invention, to pass these solutions through orifice plates (as indicated at 18^c and 18^d in Fig. 1) calibrated to deliver the required or preferred quantities of liquid at a certain definite rate of rotation of the prime mover, 30 and to maintain the solution level in the tanks by means of an ordinary float valve. The use of such plates and valves will do away with the necessity of any hand regulation whatever except control of the speed of 35 the driving engine.

The orifice plates 18^c and 18^d are diagrammatically illustrated in Fig. 2, in which 34—34 are pipe flanges, 35 is a hard metal plate having an opening or orifice 37 of predetermined area, and 36—36 are bolts for retaining the plate between the flanges. This is the simplest possible form and in actual practice one of the well known orifice plate fittings would be preferred.

45 I claim as my invention:

1. An apparatus for continuously and simultaneously producing dissimilar solutions of foam producing chemicals comprising: tanks for maintaining separate bodies of solution of said chemicals; means for separately feeding predetermined proportions of said chemicals in the form of dry powders continuously into said tanks; means for agitating the contents of said tanks to facilitate solution of said powders; means for admitting water into said tanks in predetermined proportion; pumping means for separately and continuously withdrawing said solutions from said tanks and for separately forcing said solutions to a point of intermixture thereof, and means for proportioning the quantities of said solutions delivered by said pumping means, each said proportioning means comprising a bypass communicating 65 between the discharge side and the suction

side of said pumping means, a release valve in said bypass for maintaining a predetermined pressure on said discharge side, and an orifice in said discharge between said pump and said point of intermixture for discharging a predetermined flow of liquid at said predetermined pressure.

2. An apparatus for continuously and simultaneously producing dissimilar solutions of foam producing chemicals, comprising: tanks for maintaining separate bodies of solution of said chemicals; means for separately feeding said chemicals in the form of dry powders into said tanks; means for agitating the contents of said tanks to facilitate solution of said powders; means for admitting water into said tanks to maintain a predetermined liquid level therein; pumping means for separately and continuously withdrawing streams of said solutions from said tanks and for separately forcing said streams to a point of intermixture thereof, and means for proportioning said streams, each said proportioning means comprising a bypass communicating between the discharge side and the suction side of said pumping means, a release valve in said bypass for maintaining a predetermined pressure on said discharge side, and an orifice in said discharge between said pump and said point of intermixture for discharging a predetermined flow of liquid at said predetermined pressure.

In witness that I claim the foregoing I have hereunto subscribed my name this 20th day of September, 1927.

PAUL W. PRUTZMAN.
